(57) **CLAIM**

The ornamental design for an apparatus for steaming artichokes or similar vegetables, as shown and described.

DESCRIPTION

FIG. 1 is a perspective view of an apparatus for steaming artichokes or similar vegetables.

FIG. 2 is a side view of the apparatus of FIG. 1.

FIG. 3 is another side view of the apparatus of FIG. 1.

FIG. 4 is a top view of the apparatus of FIG. 1; and,

FIG. 5 is a bottom view of the apparatus of FIG. 1.

The surface shading illustrated in the drawings is provided merely to highlight the contour of design; it is not intended to be illustrative of texture or gloss.

1 Claim, 5 Drawing Sheets

FIG. 1
